RIGHT ANGLE DRAFTING TRIANGLE
Hermann F. Ackermann, Jr., 3900 Greystone Ave.,
Riverdale, N.Y.
Filed Feb. 4, 1964, Ser. No. 342,371
7 Claims. (Cl. 33—108)

This invention relates to a 45 degree right angle triangle. More particularly, it relates to conventional 45 degree right angle drafting triangles.

Heretofore, a considerable amount of drafting was done within a relatively small area on the drawing board. This is so especially in cases involving detailed drawings, wherein there is a great amount of shifting of drafting instruments and consequent moving back and forth of the T-square or parallel edge used in such drafting operations or procedures. This would entail additional expenditure of time and effort.

The conventional 45 degree right angle triangle is easily manipulated for drawing right angle and 45 degree angle lines along the edges of the triangle when used in conjunction with the straight edge of the T-square or a parallel edge. Also, other horizontal or parallel lines are commonly drawn along the straight edge of the T-square or parallel edge. This procedure requires changing or shifting from the T-square or parallel edge to the triangle and vice versa. When having to draw many horizontal or parallel lines along the straight edge of the T-square or parallel edge, the T-square or parallel edge has to slide over the whole width of the drawing board.

In order to obviate the above undesirable features, it is an object of this invention to provide 45 degree right angle triangle having an attachment with a straight edge that can be readily and easily used in conjunction with said drafting triangle, for executing lines that are parallel with the base of the triangle without having always to use the T-square or parallel edge for that purpose.

With my invention hereinafter fully described and illustrated, a T-square or parallel edge can be kept, more often, in one position on a drawing board and used as usual for sliding the base of the triangle against, and drawing all lines that are at a right angle and all lines that are at a 45 degree angle, to the straight edge of the T-square or parallel edge. In such case most lines that are drawn parallel to the base of the triangle can be drawn along the straight edge of the above mentioned attachment.

Still another object of my invention is to provide in a right angle triangle a scale, that is marked off preferably in inches and sub-divisions of the inch, although other units of measurement may be made, for the desired and accurate spacing of any parallel lines that are executed along the straight edge of the attachment.

Furthermore, the attachment forming part of this invention has a slidable, pivotal hinge movement for swinging the attachment to a flat and fixed position on the top face of the 45 degree right angle triangle, so as to use the triangle as customary when the attachment is not in use.

Other features and advantages of the invention will be readily appreciated as the same becomes better understood by reference to the following detailed description taken in conjunction with the accompanying drawings, in which:

FIGURE 1 is a plan view of the preferred embodiment of the invention with a movable attachment in a closed position disposed on top of a 45 degree right angle drafting triangle.

FIGURE 2 is a plan view similar to FIGURE 1 of the invention, but showing the attachment in an open extended position and ready for use.

FIGURE 3 is an exploded, detail, and cut-away perspective view of the various parts comprising the invention, and

2

FIGURE 4 is a fragmental, partly broken away view in perspective of a modified form of the attachment embodying the invention.

Referring now to the drawings, wherein like reference numerals designate like or corresponding parts throughout the several views, there is shown in FIGURES 1 and 2 a conventional 45 degree right angle drafting triangle 10 with various modifications.

The triangle made of any suitable material is provided with an attachment 10a which comprises a flat and preferably transparent arm 11, with a straight edge 12 extending out an angle of 45 degrees from the hypotenuse edge 17 of said triangle 10. When said attachment 10a is in an open position, as shown in FIGURE 2, straight edge 12 will be parallel with the base of the triangle 10. Arm 11 is fastened by means of rivet or screw members 13, to the supporting underside of a bracket 14, the long end of said bracket having parallel edges extending outwardly parallel with edge 12, over a portion of the top face of the arm 11. The other end of said bracket 14 tapers to a wider width, jointly and integrally, to form a bearing 15 which is bored centrally or the end is turned over itself to fit and slide evenly on a rod 16. Said rod 16 is held in a fixed position, with the axis of said rod being parallel to the hypotenuse edge 17 of the triangle 10. Rod 16 is inserted at both ends in bearings 18 and 19, which are bored to fit or hold both ends of the rod 16. The bearings 18 and 19 are integrally connected to flanges 20, and have holes 21 in said flanges for riveting or screwing said flanges securely to the top face of hypotenuse edge 17. It will be noted that said flanges are disposed near the two apices that form the hypotenuse of the triangle 10, thus holding the rod 16 in a firmly fixed position over the top face of the triangle 10 and parallel with edge 17.

In FIGURE 1, it will be noted that the attachment 10a is shown in a closed position and lying flat on the top face of the 45 degree right angle triangle 10, and that straight edge 12 is now parallel with edge 22 of the triangle, said edge 12 being perpendicular to the base leg 22a of the triangle.

On rod 16, between one end of the bearing 15 and the end of the bearing 18, there is provided a compression spring 23. In its closed position, the free end of the arm 11 meets a strike 24 secured to the top face of the triangle 10 and near the apex of the 90 degree angle of said triangle. The tension created by spring 23, serves to keep the attachment in a closed position between the rod 16 and the strike 24. Said strike 24 is rabbeted where it meets the free end of the arm 11. The free end of the arm 11 is provided with a lip 25 that fits into the rabbeted part of the strike 24, thus holding said attachment in a locked position when desired.

Attachment 10a is released by pressing the bearing 15 against the spring 23 and in the direction of the bearing 18, thus releasing the lip 25 from the rabbeted strike 24. It will be noted that bearing 15 is bored, the axis of said bore being at a 45 degree angle to the straight edge 12, so as to pivot centrally on the rod 16. Thus said attachment is revolved from the closed position to lay flat and on the same plane with the triangle 10. Straight edge 12 of the arm 11 is then parallel with the base 22a of the triangle 10, see FIGURE 2.

A pointer 26, forming part of bracket 14, is provided with the edge of said pointer being parallel with edge 12 of arm 11. Said edge is located near the bearing 15, to ride over the top face of the triangle, adjacent and parallel with hypotenuse edge 17. The top face of the triangle is provided with scale lines 27 engraved thereon. Said lines are provided near hypotenuse edge 17 to be under the pointer 26. Lines 27 are parallel with the edge of the pointer 26, said lines being divided into inches

and sub-divisions of the inch or of any desirable unit of measurement such as centimeters and millimeters. Pointer 26 may be readily brought into registry with a selected scale line 27 for measuring the desired distance between any parallel lines that are executed along straight edge 12 of arm 11.

Referring now to FIGURE 3, further details show more fully the same and other features of the preferred invention in FIGURES 1 and 2, wherein there is provided an open slot 28. Said slot 28 has two long sides 30 running parallel with the hypotenuse edge or side 17 of the 45 degree right angle triangle 10. Also, said slot is equal and continual in profile along its full length and is located midway between the hypotenuse edge 17 and the opposite edge, from edge 17, thereby forming a triangular cut-out 29. Slot 28 terminates, at both ends, slightly short of the two apices that form the hypotenuse side of the triangle 10, the ends of said slot being cut at right angles to the long sides of slot 28. The long sides of slot 28 are concave in profile along their full length; and near the top side of the triangle 10. The concave sides 30 have an arc radius equal to the outside radius of the bearing 15, whereby the concave sides 30 form a continual recess, at the top side of triangle 10, to permit parallel slidable movement of the bearing 15 in said concave recessed sides 30.

Bearings 18 and 19 are bored centrally and are on the same axis. Also, they have a radius equal to the bore radius in the bearing 15, and an outside radius, concentric with said bores, equal to the outside concentric radius of bearing 15.

Bearings 18 and 19 have flanges 20, integrally attached thereon, with the underside of the flanges 20 resting flat on the top side of the triangle 10 and at the extreme ends of the slot 28, with the bore openings of the bearings 18 and 19 being in direct opposite relation to each other. Flanges 20 are provided with openings or holes 21 to receive rivets or screws 31 for fastening said flanges 20 to the top face of the triangle 10, thereby holding the bearings 18 and 19 in a fixed position, with the underside of said bearings resting in the concave sides 30 at the extreme ends of slot 28.

Triangle 10 is also provided with holes 32, bored to be in direct relation to the flange holes 21, and are of the same size to jointly receive the rivets or screws 31, for fastening said flanges 20 to the top face of the triangle 10, as above explained. Rivets or screws 31 being countersunk on the underside of the triangle 10, leave no protrusions on the underside of said triangle. The bores in the bearings 18 and 19 receive a sufficient portion of the extreme ends of the rod 16 to retain said rod. Bores in the bearings 18 and 19 stop on the inside to abut the flat ends of rod 16, thus holding said rod in a fixed position, wherein the axis of said rod 16 will be parallel with the hypotenuse edge 17 of the triangle. Rod 16 is inserted in the constant diameter of the bore in the bearing 15, thus placing the bearing 15 in a position for slidable and parallel movement in the concave recessed slot 28, along the hypotenuse side of the triangle 10, as previously mentioned.

When attachment 10a is open and in its proper relation to the triangle 10 as described, the underside of the extended end of bracket 14 will be on the same plane as the top side of the triangle 10, means being provided to fasten the extended end of the bracket 14 to a sufficient portion of the top side of the arm 11. Said means are holes 33 through the extended end of the bracket 14 so as to line up with holes 34 through the arm 11. Said holes 33 and 34 are of the same size to jointly receive rivets or screws 13 for steadfastly securing said arm to the underside of the bracket 14. Rivets or screws 13 are countersunk, to leave no protrusions of the same on the top face of the extended end of the bracket 14 nor on the underside of the straight edge arm 11.

With the attachment in its open position on a drawing surface, the underside of the arm 11 will be on the same plane as the underside of the triangle 10, and the straight edge 12 will be at a 45 degree angle to the triangle edge 17, making said straight edge 12 parallel with the base of the triangle 10. Thus the straight edge 12 meets the edge 35 at a 45 degree angle so that the edge 35 can abut edge 17 and cooperate for slidable movement of the arm 11 along the hypotenuse edge 17 of the triangle 10, while the straight edge 12 will always be parallel with the base of said triangle 10.

The upper corner of hypotenuse edge 17 of the triangle, and the lower corner of the edge 35 of the arm, are slightly rounded along the full length of each to allow for clear passage when the arm 11 is swung open to lay flat on the same plane with the triangle 10, thus allowing clearance for said edges 17 and 35 to abut properly.

On the top face of the 45 degree right angle triangle 10, a flat and raised parallel edged member serving as a spacer 36 is provided. Said spacer 36 runs parallel with and adjacent edge 22 that is perpendicular to the base of said triangle. Spacer 36 is permanently attached to the top face of the triangle, with the lower end of same tapering to a wider width, and integrally forming the rabbeted strike 24. Spacer 36 fills the space between the top face of the triangle 10 and a portion of the top face of the arm 11, near the straight edge 12 for said arm to lay flat and even when the attachment is in a closed position, such as shown in FIGURE 1.

Another spacer 37 serving as a stop, is provided. The top face of said spacer 37 is on the same plane as the top face of the spacer 36. Spacer 37 is permanently attached to the top face of the triangle 10, and located under a small portion of the face of the arm 11, near the edge 35, so as to abut the side of the bracket 14 when the attachment is in a closed position. This keeps the attachment in true alignment. It is obvious from the foregoing description that the 45 degree right angle triangle can be made of any workable size, but the larger the triangle is the longer the arm of the attachment can be, in proportion to the size of the triangle.

The above described straight edge attachment to conventional 45 degree right angle drafting triangles is for a precision-made drafting instrument. There is provided according to my invention a more simple design working on the same principle as the attachment described in connection with FIGURES 1, 2 and 3. This is described, herein following, and is shown in FIGURE 4.

The 45 degree right angle triangle 10 partly shown in FIGURE 4 is for means of conserving space and designated by the numeral 44, with one end of the hypotenuse edge 42 shown meeting part of the edge 45 that is perpendicular to the base of the triangle 44. The opposite end of the hypotenuse edge, not shown, is to be visualized as equal to the edge 42 as shown, but opposite hand.

The modification of this invention comprises an arm 39 similar to the arm 11 as described in connection with FIGURES 1, 2 and 3. Said arm 39 has a straight edge 40 meeting the edge 41 at a 45 degree angle, but having no lip 25 as described in connection with FIGURES 1, 2 and 3. The edge 41 tapers to a wider width, from the body of the narrower parallel edged and extended part of the arm 39, thus affording more edge surface for the edge 41 to abut and slide against the hypotenuse edge 42 of the triangle.

The modified form of the invention, used in conjunction with a conventional 45 degree right angle triangle, is removable and is also provided with a bracket 43, said bracket being secured to the top face of the arm 39, in a suitable manner as described in connection with FIGURES 1, 2 and 3 for the bracket 14. However, bracket 43 has a different form of slidable and parallel movement along the top face, and near the edge, of the hypotenuse side of the triangle 44. One end of this bracket 43 also tapers to a wider width from the narrower parallel edged

extended end, with the underside of said tapered end riding over the top face and along the hypotenuse side of the triangle 44.

The flat underside of said tapered end of the bracket 43 is provided with a lowered portion, integral thereon, to form a tongue 46 which runs the full width of the tapered end of the bracket 43. Tongue 46 having its long sides parallel, fits in an open slot 47 located midway between hypotenuse edge 42 and opposite edge 48 that forms part of the triangular cut-out 49.

Thus slot 47 forms a parallel sided groove, running parallel with the hypotenuse edge 42, into which the tongue 46 can be inserted for the sides of said tongue to abut the parallel sides of said slot and retain the attachment for slidable and parallel movement along the hypotenuse side of the triangle 44. Arm 39 is located on the underside of the bracket 43 so as to have the edge 41 abut the hypotenuse edge 42 to cooperate with the tongue 46 when said tongue is retained in the slot 47. Said slot 47 terminates at both ends slightly short of the two apices that form the hypotenuse side of the triangle 44, with the ends of said slot being cut at right angles to the long parallel sides of said slot. The ends of said slot 47 act as a stop for the ends of the tongue 46. The bottom edges of the tongue 46 and the bottom edge 41 of the arm 39 are beveled slightly and evenly along their full lengths, thus providing easement of connection prior to the attachment being fully engaged when the attachment is lowered onto the triangle 44. The underside of said tongue 46 is slightly above the underside of said triangle 44 when said tongue 46 is fully engaged in slot 47.

Bracket 43 has a pointer 50, integral with and forming part of the bracket 43. Pointer 50 cooperates with the scale lines 51, and functions on the same principle as described in connection with the pointer 26 of FIGURES 1, 2 and 3.

Furthermore it will be noted that said attachment 10a is provided with a finger grip or handle 52, located and attached to the top side of the bracket 43. Handle 52 extends lengthwise or parallel with bracket 43, and is situated with one end of said handle over the tapered end of the bracket 43, and the opposite end of said handle extending a distance that will be partially past the edge 41 of the arm 39. Arm 39 can be of a longer length than arm 11 as described in connection with FIGURES 1, 2 and 3, since arm 11 is limited as to length to fit on the top side of the triangle 10 as described in connection with FIGURES 1, 2 and 3.

While only preferred embodiments of the invention have been shown in the annexed drawings and described in the specifications above, it is contemplated to cover any variations, changes and modifications as to use and parts of materials chosen for the purposes of the disclosure and as claimed herein, which do not constitute departures from the spirit and scope of the invention set forth in the appended claims.

What is claimed is:

1. A triangle having an attachment comprising a flat arm with top and bottom sides on the same plane corresponding with that of the triangle, a straight edge on said arm, adapted to extend from the hypotenuse of the triangle and be parallel with the base of the triangle said arm being beveled at a 45 degree angle from the straight edge, and being adapted to slide evenly against the edge of the hypotenuse, and means for retaining the said arm in a position for slidable and parallel movement along the hypotenuse, said arm comprising a bracket with one flat and parallel edged extended and thereof being mounted over the top face and parallel with the edge of said arm.

2. A triangle according to claim 1 in which there is provided a bearing symmetrical in section along the width of said arm and adapted to permit said attachment to be closed against the vertical arm of the triangle.

3. A triangle according to claim 2 provided with bear-

ing means attached at opposed ends to the hypotenuse, a rod adapted to fit in said bearing means, a slidable member having an extendable arm adapted to be moved to any position along the hypotenuse, and spring tension means between one of the bearings and the slidable member.

4. A 45 degree right angle drafting triangle comprising a flat arm having both top and bottom sides, a straight edge on said arm extending from the hypotenuse edge of said triangle parallel with the base of said triangle, an adjacent edge of said arm beveled at a 45 degree angle from the straight edge, to abut and slide evenly against the hypotenuse edge of said triangle, means for retaining said arm in a position for slidable and parallel movement along the hypotenuse edge of said triangle.

5. A triangle according to claim 4 wherein said means is a bracket having one flat and parallel edged extended end mounted over the top face and being parallel with said straight edge of said arm and being of a narrower width than said arm to leave a portion of the top face of said arm visible along the straight edge, the other end of said bracket tapering to a wider width and extending past the hypotenuse of said triangle to be over the top face of said triangle, the extreme end of said tapered end shaped, thereon forming a bearing, the flat tapered end

25 riding over the hypotenuse side of said triangle and meeting the side of said bearing, said bearing being symmetrical in section along the width of said flat tapered end in relation to the top and bottom sides of said bracket, said bearing being centrally bored with the axis 30 of said bearing at a 45 degree angle to the straight edge and parallel with the hypotenuse edge of said triangle, the axis of said bore being located midway between the hypotenuse edge of said triangle and the edge opposite that forms part of the triangular cut-out, said bearing

35 further having a continuous outside diameter, concentric with the diameter of said bore, the flat tapered end riding over the hypotenuse side of said triangle being provided with a pointer and forming part of the bracket, said pointer having an edge parallel with said straight edge, 40 to ride over and cooperate with scale lines engraved on the top face and along the hypotenuse side of said triangle, a rod held in fixed position over the top face of said triangle with the axis of said rod parallel with the hypotenuse side of said triangle, said rod being inserted

45 to fit evenly in the bore of said bearing, means for holding said rod in a fixed position, flat flanges extending on a diametrical line from the sides of second bearings with said flanges extending around the closed ends of said second bearings, the underside of said flanges resting on the 50 top face of said triangle to be near the apexes forming the hypotenuse side of said triangle, said flanges being provided with holes bored to meet corresponding holes bored through the triangle to receive rivets or screws for holding said second bearings in a fixed position on the top side of said triangle.

6. A triangle according to claim 5 wherein said means being second bearings having the same outside diameter as said first bearings, said second bearings having bores of the same diameter as said first bearing to receive a sufficient portion of the extreme ends of said rod to retain 60 said rod, the bores stop on the inside of said second bearings to form closed ends, with the flat ends of said rod to abut said stops in said bores, flat flanges forming part of said second bearings extending out on a diametrical line from the sides of said second bearings with said flanges extending around the closed ends of said second bearings, the underside of said flanges resting on the top face of said triangle to be near the apexes forming the hypotenuse side of said triangle, said flanges being provided with holes bored to meet corresponding holes bored

65 through the triangle to receive rivets or screws for holding said second bearings in a fixed position on the top side of said triangle.

7. A triangle according to claim 6 having a parallel sided open slot through and along the hypotenuse side

75

of said triangle parallel with the hypotenuse edge of said triangle directly under said rod, the upper edges of the long parallel sides of said slot being concave in profile along their full lengths, said concave sides having an arc radius equal to the outside radius of said first and second bearings, said slot terminating at both ends and being under and flush with the underside of said second bearings, with the underside of said first bearing resting in said concave sides for slidable and parallel movement of said first bearing in said concave sides, a flat member serving as a spacer having its long end parallel edged and mounted on the top face of said triangle to be parallel with and near the edge of said triangle that is perpendicular to the base of said triangle, the lower end of the flat and parallel edged spacer tapering to a wider width from the narrower parallel edged end, said tapered end of said spacer being located near the base of said triangle, said tapered end of said spacer being thicker than the narrower parallel edged end of said spacer, to form a strike and having a rabbeted edge on said strike to receive a lip formed on the free end of said arm, the first bearing being mounted to pivot on said rod, said arm being adapted to be swung over on the top face of said triangle and said straight edge of said arm being parallel with the edge of said triangle perpendicular to the base of said triangle, with said lip on the free end of said arm engaged in the

5 rabbeted edge of said strike, a portion of the top face of said arm along said straight edge thus resting on the top of said narrower parallel edged end of said spacer, a compression spring located on said rod between the ends of the first and second bearings, for retaining said arm in a flat and locked position on the top face of said triangle, a second spacer, serving as a stop, located under a small portion of said arm and attached to the top face of said triangle, to be near the edge that is at a 45 degree bevel from said straight edge when said arm is in its closed position on the top face of said triangle, with said second spacer in a position to abut the edge of said bracket.
